UNITED STATES PATENT OFFICE.

JOHN W. COLLIER, OF LOCKPORT, NEW YORK, ASSIGNOR TO JOHN McLEAN,
OF SAME PLACE.

MACHINE FOR SECURING HANGERS TO THE CORNERS OF BOOKS.

SPECIFICATION forming part of Letters Patent No. 443,498, dated December 30, 1890.

Application filed May 23, 1890. Serial No. 352,915. (No model.)

To all whom it may concern:

Be it known that I, JOHN W. COLLIER, a citizen of the United States, residing at Lockport, in the county of Niagara and State of New York, have invented certain new and useful Improvements in Machines for Securing Hangers to the Corners of Paper-Covered Books; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to the improvements in that class of machinery employed in securing hangers to the corners of paper-covered books, almanacs, and pamphlets, its object being to produce a machine which is automatic in all its operations after the stock has been fed into the same; and it consists in a machine the combination and arrangement of which will enable me to punch a hole in the corner of a paper-covered book, almanac, pamphlet, &c., and at the same time pass a string or cord through the same, cutting the string at the desired length, and tying its ends together.

My invention further consists in other details of construction, all of which I will now proceed to definitely describe and claim.

In the drawings, Figure 1 is a front elevation of my improved punching and stringing machine. Mounted upon the main shaft of the machine are three wheels carrying cams, and which for convenience I have numbered 1, 2, and 3. Figs. 2 and 3 are detail views showing the operation of the cams on the first wheel. Fig. 4 is a detail view showing the operation of the cams or projection on the second wheel, and Fig. 5 is a diagram of the grooved cam on the periphery of the second wheel. Figs. 6 and 7 are detail views of the cams on the third wheel. Fig. 8 is a top view of my improved machine. Fig. 9 is an enlarged top view showing the shears, nippers, and slide and their operation. Figs. 10 and 11 are detail views of the nippers employed for drawing and holding the string or cord while the knot is being tied. Fig. 12 is a detail view

of the spring-pressed catch for holding the end of the string as the punch or needle rises. Fig. 13 is a detail view of the punch or needle. Fig. 14 is a detail view showing the knotter as it rests in its carriage. Figs. 15, 16, 17, 55 and 18 are detail views showing the operation of the knotter. Fig. 19 is a detail view of the cast-off for releasing the cord from the knotter. Fig. 20 is a detail view showing the friction-pulleys by means of which the power 60 is applied to my improvement, and Fig. 21 is a detail view showing one of the cylinders of the knotter.

Referring to the drawings, *a* is the frame, having at its ends the brackets *a'* *a'*, their lower ends being secured together by the cross-bar *a*². Loosely journaled in these brackets *a'* *a'* is the main shaft *b*, upon which are mounted the cam-operating wheels 1, 2, and 3, numbered successively from the right 70 to the left as they appear on the main shaft in Fig. 1.

On the right-hand side of the first wheel is arranged a cam *c*, which operates a vertical rod *c*², having the pin *c'* resting in the groove 75 of the cam *c*. This vertical rod *c*² passes up through the frame *a*, and is secured to the vertical rod *d* by a short arm *d*². The rod *c*² is held in a perpendicular position by a short band or plate *c*³, secured to the lower end of 80 the bracket *a'*, and between which the rod *c*² slides. The rods *d* *d'* have a perpendicular reciprocating motion in the brackets *f* *f'*, which are rigidly secured to the top of the frame *a* by the rod *f*. At the lower end of 85 the rod *d'* is secured the punch or needle *e*, (more clearly shown in Fig. 13,) its upper end *e'* being enlarged for securing the same to the rod *d'*, and its lower end or point *e*² being made V-shaped to facilitate its cutting or 90 punching in passing through the paper book. A grooved recess *e*³ is longitudinally arranged, starting from a point near the top of the needle and running down to its eye on one side, and running from the eye down to the point 95 on the other side for the reception of the string or cord. On the left-hand side of the first wheel is arranged the cam *g* for operating the pivoted rod *g*². This rod *g*² is pivoted at its lower end to the cross-bar *a*², and 100

having a pin g' resting in the groove of cam g , its upper end being loosely pivoted to the slide h , which is made to slide back and forth in the frame a . This slide h (see Fig. 9) is connected to the levers i , i' , and i^2 by a short upwardly-projecting arm h' , and by which means the shears j are operated. Also, upon this slide h are arranged the nippers k , formed of two steel springs or plates secured to the slide h , and having the holes k' arranged in their outer ends (which extend beyond the slide) to allow the punch or needle to pass through them. These steel springs or plates as they approach the paper book or pamphlet to be operated upon are separated by a short wedge k^2 , thus placing one plate above and one below the point of operation, thus forming a die for the punch or needle when passing through the same. Two small projections $l l$ are also arranged on the left-hand side of the first wheel, and are so placed as to open the spring-catch m to receive the end of the spring or cord and release the same.

At the right-hand side of the second-wheel 25 I have arranged the cam or projection n for operating the slide n' in the frame a . A short pivoted lever n^2 , pivoted to a downwardly-projecting arm or hanger a^4 , has arranged at its lower end a short pin n^3 , which rides along 30 the right-hand side of the second wheel and operates the pivoted lever n^2 as it passes over the cam n , the pivoted lever n^2 being connected to the slide n' by the rod n^4 . (see Fig. 5,) the lever n^2 and the slide n' being returned 35 to their normal position by the spiral spring n^5 , embedded in the frame a , as seen in dotted lines in Fig. 8. The slide n' has arranged on its upper surface two metallic bands or strips slightly raised above the surface of the slide for the reception of the paper book or pamphlet to be operated upon and serve to hold the same in position. Its object in passing back and forth in the frame a is to shove the stock onto the endless belt 45 or carrier p , where it passes off, and as the slide returns to its normal position it is again fed for the next operation.

On the periphery of the second wheel is arranged a grooved cam q , into which the pin q' rests, projecting downwardly from the carriage q^2 , into which is journaled the knotter r . This knotter r moves with the carriage q^2 back and forth in the frame a , being operated by the pin q' resting in the groove q .

On the left side of the third wheel is arranged the cam o , which operates the pivoted rod o' , which is pivoted at its lower end to the cross-bar a^2 , and having a small pin o^2 , secured to its center, projecting into the groove 60 of the cam o . A segmental gear s , mounted in the bracket q^3 , projecting from the carriage q^2 , is connected to the pivoted rod o' at its upper end by the connecting-rod o^3 . This connecting-rod o^3 is jointed, so as to admit of 65 its perfect operation while the carriage is passing back and forth in an opposite direction to the lever o' . It will be seen that the

motion given to the pivoted arm o' by the cam o gives a reciprocating motion to the segmental gear s .

On the opposite side of the third wheel are arranged the cams or projections $t t'$. A short lever u , pivoted to the end of the brackets q^3 and having its upper end resting against the rear end of the knotter r , its lower end extending downwardly and coming in contact with the projection $t t'$ on the left-hand side of the third wheel, causes its upper end to press against the rear end of the knotter r . This knotter r is constructed of two cylinders $r' r^2$, one within the other, the outer cylinder r' being loosely journaled in the carriage q^2 , but securely held from lateral displacement, and having at its rear end a small pinion-wheel r^3 , which intermeshes with the segmental gear s . The forward end of this cylinder r' is cut in cross-section, having a narrow tapering segment r^4 , the end of which is formed into a spiral-shaped hook r^5 , as shown in Figs. 14 to 18. The inner cylinder r^2 is held within the cylinder r' by a pin r^6 , but given a limited lateral play by reason of the elongated slot through which the pin r^6 passes, as shown in Fig. 21. At the rear of the cylinder r^2 and encircling its outer surface is the spiral spring r^7 , which presses against the rear end of the cylinder r' at one end and a projecting head r^8 at its other end, upon which the pivoted lever u also acts. The forward end of this inner cylinder r^2 is formed the same as that of the cylinder r' , having the segmental tapering projection r^9 and spiral-shaped hook r^{10} . These spiral-shaped hooks and tapering projections appear as but one hook and projection when in their normal position, as seen in Fig. 15; but as the pivoted lever u passes over the projection t on the third wheel it will cause the inner cylinder r^2 to be moved forward within the cylinder r' , thereby grasping the ends of the string or cord, as seen in Fig. 17, and as the lever passes over the second projection t' , the knot then being tied, the ends of the string are released.

To the rear of the main shaft and running parallel with it is the shaft u , resting loosely in the brackets $a' a'$ and having rigidly secured thereto the short arms or brackets $w' w'$, extending upwardly, and into which is loosely journaled the auxiliary shaft w^2 , upon which is mounted the pulley-wheel w^3 and friction-pulley w^4 .

Rigidly secured to the shaft w is the manipulating-lever w^5 , by which means the friction-pulley w^4 is brought to bear against a larger friction-pulley x , mounted on the main shaft b , thus imparting the motion to the machine.

At the left-hand side of the main shaft (see Fig. 1) is mounted the small grooved pulley y , which is connected to the pulley y' by the cord or belt y^2 , which operates the conveyer or carriers p , which carries off the stock as the operation is completed.

In operation the paper book or pamphlet is first placed upon the slide m' , being held in position by the metallic strips or bands projecting over it. The nippers k , arranged on the slide h , which is operated by the cam g , then approaches the book and are opened or separated by the wedge k^2 , one of the plates passing above and the other below the book at the point of operation and forming a die for the punch or needle e , which is now caused to pass down by the action of the cam c . This needle e , having the cord or string threaded through its eye with end protruding, passes down through the holes k' in the ends of the nippers k , punching the opening in the corner of the book, and at the same time carrying the string or cord with it. As the punch or needle e approaches its lowest point, the spring-catch m is opened by one of the projections l on the left-hand side of the first wheel, and the needle passing between it, the protruding end of the string or cord passing between the parts m' m^2 of the spring-catch, and as the catch is released from the projection l the tension of the spring holds the end of the string or cord, which is now drawn through the eye of the needle as it rises. After the point of the needle has reached its highest point, which is above the shears j , the slide h , with the nippers k , starts to move back to its normal position, by which action the shears are made to close, cutting the cord or string slightly below the needle-point, and the other projection l on the first wheel of the main shaft opens the spring-catch, releasing the lower end of the string, which is drawn back by the nippers k , as shown on Fig. 11, holding the two ends of the string or cord, which is now cut from the spool. While the string or cord is held in this position the knotter r , by means of the pin q' resting in the grooved cam q , is carried under the string, which drops into the spiral-shaped hooks r^5 r^{10} , as seen in Fig. 15. The cylinders r' r^2 , with their tapering segments and spiral-shaped hooks, are then caused to revolve by means of the cam o on the third wheel, being connected therewith by the pivoted rod o' , having the pin o^2 and being in turn connected to the segmental gear s by the rod o^3 , this segmental gear s intermeshing with the pinion r^3 of the knotter r , and as the knotter revolves the string or cord is wound once around it, as seen in Fig. 16. The lower end of the pivoted lever is now brought in contact with the projection t on the third wheel of the main shaft, thus causing the spiral-shaped hooks r^5 r^{10} to separate, the nippers still holding the ends of the string or cord and drawing them between the hooks, where they are released from the nippers (see Fig. 17) and firmly held by the hooks, the pressure of the pivoted lever u having been released and the hooks brought together by the action of the spiral spring r^7 . The carriage q then returns to its normal position, and when in that position a stationary point or scraper rests against the outer surface of

the spiral-shaped hook r^5 in a groove r^{11} . The segment, returning to its first position, causes the pinion r^3 to revolve with its cylinders r' r^2 in the opposite direction, and the stationary point or scraper coming in contact with the string or cord forces it over the ends of the hooks, immediately after which the hooks are slightly separated by the short projections t' , which releases the ends of the string, as seen in Fig. 18. The wedge k^2 , employed for opening the nippers k , is secured only at one end, the other end being free for the loop to be released as the book is shoved upon the carrier p .

I claim—

1. A machine for securing hangers to the corners of paper-covered books, consisting, essentially, of a reciprocating punch or needle connected to a perpendicular lever operated by a cam, said punch or needle having a V-shaped point or end and being threaded with a string or cord with end protruding, and being passed through holes in the ends of a pair of nippers and forced through a book located between the ends of said nippers, a spring-catch adapted to receive and hold the end of the string or cord as the needle rises, said spring-catch releasing the string or cord as it is being drawn in a horizontal position by the nippers at the same time the cord is automatically cut and drawn through the nippers, said nippers holding the two ends of the string or cord, and an automatic knotter consisting of two cylinders, one within the other, and having hooks and projections, by which means the ends of the string or cord are tied together, substantially as shown and described.

2. In a machine for securing hangers to the corners of paper-covered books, a knotter consisting, essentially, of two cylinders, one within the other, being provided at their forward end with tapering projections and spiral-shaped hooks, and being securely held together by a pin passing through them, the inner cylinder having a lateral play, being limited by the elongated slot through which the pin passes, and the outer cylinders being provided at its rear end with a pinion intermeshing with a segmental gear, giving a reciprocating revolving motion to the same, substantially as shown and described.

3. In a machine for securing hangers to the corners of paper-covered books, a punch or needle, being secured at its upper end to a reciprocating rod and having an elongated groove or recess cut in its surface running nearly to its upper end from one side of the eye and running to the point or lower end on the opposite side for the reception of the string or cord, substantially as shown and described.

4. In a machine for securing hangers to the corners of paper-covered books, the combination of a punch or needle secured to a reciprocating rod and threaded with a string or cord adapted to pass through the corner of a book, and a spring-pressed catch for retain-

ing the end of the string or cord and drawing it through the eye of the needle as it rises, said spring-pressed catch being operated by cams or projections, substantially as shown 5 and described.

5. In a machine for securing hangers to the corners of paper-covered books, a pair of nippers consisting, essentially, of two steel plates secured together and moving back and forth 10 on a slide or carrier, said steel plates having their ends provided with holes or openings for the reception of the punch or needle and

adapted to draw the string after being cut from a perpendicular to a horizontal position and hold the ends of the same until they have 15 been tied together, substantially as shown and described.

In testimony whereof I have signed my name to this specification in the presence of two subscribing witnesses.

JOHN W. COLLIER.
